UNITED STATES PATENT OFFICE.

JOHN COURTENAY, OF AVIEMORE, ELSIES RIVER HALT, CAPE COLONY.

HARROW OR CULTIVATOR.

No. 922,671.

Specification of Letters Patent.

Patented May 25, 1909.

Application filed February 6, 1909. Serial No. 476,711.

To all whom it may concern:

Be it known that I, JOHN COURTENAY, gentleman, a subject of the King of Great Britain, residing at Aviemore, Elsies River 5 Halt, Cape Colony, have invented new and useful Improvements in Harrows or Cultivators, of which the following is a specification.

This invention relates to improvements in 10 harrows or cultivators especially such as are employed in the cultivation of lucerne, and particularly consists in an improved construction of the teeth or tines of such implements.

15 The invention is illustrated in the accompanying drawings in which—

Figure 1 shows a view of a complete cultivator; Fig. 2 shows a side view and Fig. 3 an edge view of one of the tines 20 secured to its support. Fig. 4 is a cross section through the support showing the method of securing the tine. Fig. 5 illustrates a slight modification.

Referring to Figs. 2, 3 and 4 each tine 25 consists essentially of a flat pointed blade *a* of the nature of a small plow, the blade being twisted in its length. This blade is secured to or preferably formed on the end of a spiral of iron or steel rod *b* preferably 30 tempered to a suitable degree of elasticity. At its further end *c* this rod is flattened and is curved around a hollow support or pipe *d*. The rod may be secured to its support in any suitable manner, but preferably a 35 staple *e* is provided, the loop *f* of which loosely incloses the round part of the rod, while its screwed stem *g* passes through the tube and the flattened end of the rod and receives a nut *h* (and if desired a lock nut) 40 by which the tine is kept in position. This method of support gives considerable elasticity to the blade, for the spiral *b* is able to yield a good deal against the main thrust while also the rod can move laterally a little 45 in the loop *f* of the staple. A number of these tines, say eight, are secured upon a single support *d*, and as shown in Fig. 1, there may be two such supports arranged in the cultivator. As will be seen from this 50 figure the supports *d* are secured at the ends in bars *k*. These bars are further joined by cross pieces *l* extending across the whole width of the cultivator, and to the bars *l* are attached metal pieces *m* which are 55 adjustably mounted upon the main beam *n* of the implement by means of screws *p* passing

through bosses *q* in the parts *m* and bearing against suitable plates upon the beam *n*. The wheels of the vehicle are secured to the beam *n* by means of looped pieces *r* so 60 as to allow of the vertical adjustment of the frame formed by the bars *k* and *l* by means of screws *p*. This adjustment obviously determines the depth to which the tines will penetrate into the ground. A further movement can be given to the tines 65 since their supports *d* are mounted revolvably in the end pieces *k*. A handle *s* working against a notched segment *t* operates links *v* secured to the supports *d* so as to turn the 70 tines upward or downward. If desired, the lower part of the handle *s* may as shown take the part of a link *v*.

It has been noted above that a little lateral play is given to the tine since the end 75 of its support can move very slightly in the loop of the staple. Moreover the support being flexible, or rather springy, can yield when pressure is applied to the point of the tine and the twisted form of this point as 80 assists it in finding its way among the roots of crops. The tine has thus all the effectiveness of a spring harrow or cultivator tooth while further it acts with better effect as a 85 scarifier or scuffler and it is not so likely to 85 damage a young crop; moreover this method of securing the separate tines to a common rod obviously allows of any one being removed by itself.

By reference to Fig. 3 it will be seen that 90 the pointed, flat and twisted blade *a* is so disposed that it stands vertically edgewise, so as to make a vertical cut through the soil, while the twisted form of the blade, aided by its lateral and vertical vibrating movements renders it very effective as a scarifier 95 or scuffler, in stirring up the soil, as above referred to. By using round metal rods for the bodies *b* of the tines or teeth the expense of manufacture is somewhat less than it 100 otherwise would be.

It will be clear that modifications may be introduced into the form above described in detail. As has already been indicated it may be convenient to make the whole of the 105 tine and its support in one piece in which case the material employed should preferably be tempered steel. Modifications may of course be made in the exact shape of the support and similarly the point or blade 110 may be twisted right or left handedly as may be desired. For example, as is indi-

cated in Fig. 5, the spiral support may have more than one complete turn. Finally as has also been suggested the tines may be secured in any other suitable way to a common tube or rod.

5 What I claim is:

1. A tine for harrows or cultivators, comprising a resilient spiral shank having at its working end a flattened and pointed blade 10 which is so disposed as to stand edgewise vertically.
2. A tine for harrows or cultivators consisting of a resilient spiral shank round in cross section and having a flattened and 15 pointed twisted blade at its working end, and a flattened attaching end, combined with a support for said tine and a staple passing through said support and the flattened attaching end of said tine and having 20 a looped portion loosely inclosing said round resilient shank.
3. A tine for harrows or cultivators comprising a resilient spiral shank having at its working end a flattened and pointed 25 blade which is so disposed as to stand edge-wise vertically, said tine having a shank which is round in cross-section and which

has a flattened attaching end, combined with a support for said tine, and a staple passing through said support and the flattened attaching end of said shank and having a looped portion loosely inclosing said round resilient shank.

4. A tine for harrows or cultivators comprising a resilient spiral shank round in 30 cross section with a flattened attaching end and a flattened, twisted and pointed working end.

5. A tine for harrows or cultivators comprising a resilient spiral shank round in 40 cross section with a flattened attaching end, and a flattened, twisted and pointed working end, combined with a support for said tine, and a staple passing through said support and the flattened attaching end of said tine 45 and having a looped portion loosely inclosing said round resilient shank.

In testimony whereof I have signed my name to this specification in the presence of two subscribing witnesses.

JOHN COURENAY.
